UNITED STATES PATENT OFFICE.

RICHARD L. MAINWARING, OF BROOKLYN, NEW YORK.

CLEANING AND POLISHING COMPOSITION.

1,239,416.

Specification of Letters Patent.

Patented Sept. 4, 1917.

No Drawing.

Application filed April 18, 1917. Serial No. 162,411.

To all whom it may concern:

Be it known that I, RICHARD L. MAINWARING, a subject of the King of Great Britain, and a resident of the borough of Brooklyn, in the county of Kings and city and State of New York, have invented a new and useful Cleaning and Polishing Composition, of which the following is a full, clear, and complete disclosure.

10 My invention relates to a composition designed particularly for use in the cleaning and polishing of furniture, pianos, automobiles, and various other painted, varnished or enameled surfaces, and is particularly adapted to remove therefrom dirt, grease and imperfections, and to give the surface a high polish and a glossy appearance. Further advantages of my invention are its ease and economy of preparation and simplicity of application to the surface which is to be treated.

The composition is prepared from the following ingredients, preferably in the proportions stated:

25 White beeswax—14 ounces by weight; Benzin—1 gallon; Wood alcohol—3 fluid ounces; Concentrated ammonia—2 fluid ounces; Oil of mirbane—3 fluid ounces.

30 The purpose of the oil of mirbane is to neutralize the odors of the other ingredients. The ingredients are preferably mixed according to the following method:—First the beeswax is dissolved in the benzin; to facilitate this, the beeswax should be broken up into small pieces. The benzin and beeswax are allowed to stand for a period of about twenty four hours. When the beeswax is

thoroughly dissolved, the wood alcohol, concentrated ammonia, and oil of mirbane are 40 stirred in. This completes the preparation of the composition, and it is then ready for use.

It is applied to the articles to be cleaned and polished by moistening a sponge or 45 cloth with it and rubbing it on. The article is then rubbed with a soft cloth, chamois or other like material, and a clean, highly polished surface is the result.

The stated proportions of the ingredients 50 of my cleaning and polishing composition may be somewhat varied without going beyond the scope of my invention.

Having now described my invention, what I claim is:

55

1. A cleaning and polishing composition, consisting of beeswax, benzin, alcohol and ammonia.

2. A cleaning and polishing composition, consisting of beeswax, benzin, alcohol, ammonia, and a substance for the purpose of 60 neutralizing the odors of the other ingredients.

3. A cleaning and polishing composition, consisting of white beeswax, benzin, wood 65 alcohol, concentrated ammonia, and oil of mirbane.

4. A cleaning and polishing composition, consisting of the proportions of 14 ounces by weight of white beeswax, to 1 gallon of 70 benzin, to 3 fluid ounces of wood alcohol, to 2 fluid ounces of concentrated ammonia, to 3 fluid ounces of oil of mirbane, substantially as described.

RICHARD L. MAINWARING.
